[57] ABSTRACT

A radiator device includes a plurality of filler plates made from a low heat conductivity and high specific heat such as for example gadolinium/rhodium and a plurality of spacer members disposed on each one side of the filler plates to form a fluid flow passage and a housing member accomodating the spacer and the filler plates.

FIG. 8

RADIATOR DEVICE

BACKGROUND OF THE INVENTION

1. Field of the Invention

This invention relates to a radiator and more particularly to a multi-plate type radiator particularly used in a Stirling cycle or Gifford cycle refrigerators.

2. Prior Art Statement

In a radiator for refrigerators, it is important to have a heat conducting area as large as possible and to increase the rate of space occupying. Conventionally, for example, a Japanese Pat. Publication No. 43(1968)-10939 discloses a type of radiator illustrated in FIGS. 1 and 2. Therein, a belt shaped paper sheet 1 has a pair of lead layers 2 attached to both sides of the paper sheet 1. An upper side of the lead layer 2 has a plurality of bell shaped projections 3 for defining fluid flow passages when it is wrapped up as seen in FIG. 2.

In this conventional type, however, the material used should be restricted to a soft and relatively high specific heat due to the necessity of roller finish on the front layer so as to have a constant thickness. Thus, many conventional devices have used lead materials as a radiator plate members. Since the lead can be used in a refrigerator of 10K degree at most and it is impossible to apply to a refrigerator which needs a lower cooling capacity.

It is, therefore, an object of the present invention to provide a radiator for a refrigerator having lower cooling capacities.

It is another object of the invention to provide a 35 radiator device for a refrigerator using non-lead material for a radiator filler members.

BRIEF DESCRIPTION OF THE DRAWINGS

These and other objects of the invention will be apparent from the following detail description of the invention with reference to the attached drawings in which:

FIG. 1 is a perspective view of a filler of the radiator according to a conventional device; 45

FIG. 2 is a front view of the filler of FIG. 1 but showing in wrapped condition.

FIG. 3 is a perspective view of the filler assembly according to a first embodiment of the present invention; 50

FIG. 4 is a cross sectional view of the filler assembly of FIG. 3;

FIG. 5 is a similar view to FIG. 3 but showing a different embodiment of the invention;

5 FIG. 6 shows a single filler plate of a further embodiment of the invention;

FIG. 7 is similar to FIG. 4 but showing a different embodiment of the invention; and

10 FIG. 8 is an exploded view of the assembly illustrated in FIG. 7.

DETAILED DESCRIPTION OF THE EMBODIMENTS

In FIG. 3, fillers 4 are made from a material having a 15 high specific heat and relatively low heat conductivity such as gadolinium/rhodium or gadolinium/erbium/-rhodium.

A plurality of spacers 5 are provided at two edge portions of each side of the filler 4 so as to define fluid 20 passages 6 therebetween thereby to form a filler assembly. This assembly is housed in a housing 9 (in FIG. 4) having an inlet 7 and an outlet 8 to form a radiator device. The cross sectional area of the passage 6 can be changed by changing the thickness of the spacers 5. 25 Instead of using spacers 5, each filler 4 may be provided with a pair of flanges 10 integrally formed with the filler as viewed in FIG. 5. Another embodiment is illustrated in FIG. 6 wherein the spacer or flange may be in the shape of projections 11, as shown.

30 In FIGS. 7 and 8, the filler assemblies 12, 13 of FIG. 3 are disposed in the radiator housing at a right angle to each other and stacked up so that the heat conductivity may be reduced in the fluid flow direction.

What is claimed is:

1. A radiator device comprising:
a plurality of filler plates, each of said plates being made from a material having a low heat conductivity and high specific heat;
a plurality of spacer means positioned on each side of said filler plates in the form of projections projecting from said each side to form a fluid passage therebetween;
a housing having an inlet and an outlet substantially centrally positioned with respect to the housing for a fluid and enclosing a filler assembly formed by said filler plates and spacer means; and
at least three of said filler assemblies positioned in said housing so that each said assembly is positioned at an angle to an adjacent filler assembly so as to reduce heat conductivity in a fluid flow direction.
